UNITED STATES PATENT OFFICE.

KASBERG C. GEELE, OF FINLEY, NORTH DAKOTA.

VALVE-GEAR.

SPECIFICATION forming part of Letters Patent No. 703,569, dated July 1, 1902.

Application filed June 13, 1901. Serial No. 64,388. (No model.)

To all whom it may concern:

Be it known that I, KASBERG C. GEELE, a citizen of the United States, residing at Finley, in the county of Steele, State of North Dakota, have invented certain new and useful Improvements in Valve-Gear; and I do hereby declare the following to be a full, clear, and exact description of the invention, such as will enable others skilled in the art to which it applies to make and use the same.

This invention relates to valve mechanisms for steam-engines; and it has for its object to provide a simple and efficient mechanism which is applicable to different styles of engines and wherein the valve will be operated in such manner as to secure a most efficient cut-off.

A further object of the invention is to provide a simple arrangement for reversing the engine, other objects and advantages of the invention being understood from the following description.

In the drawings forming a portion of this specification, and in which like numerals of reference indicate similar parts in the several views, Figure 1 is a longitudinal sectional view through an engine equipped with the present invention. Fig. 2 is an elevation of the valve.

Referring now to the drawings, there is shown the invention as applied to a single-expansion engine, wherein the cylinder 40 has a piston 41 provided with a rod 42. On the cylinder is a steam-chest 43, and between the steam-chest and the cylinder is a valve-chamber 44, which communicates at its ends with the cylinder. In the valve-chamber is disposed a reciprocatory valve 45, having the hollow plugs 46 and 47 adjacent to its ends and which project downwardly and into the upper portion of the cylinder.

The plugs 46 and 47 are hollow and communicate with the steam-passages 48 and 49 in the valve. The passages 48 and 49 lead inwardly and then upwardly through the upper side of the valve and are adapted to register with the ports in the bottom of the steam-chest. There are two inlet-ports 50 and 50' and two outlet-ports 51 and 52, and the passage 48 is adapted to register alternately with ports 50 and 51, while the pas-

sage 49 is adapted to register alternately with the ports 50' and 52, so that when one passage is in registry with an inlet-port the other passage will be in registry with an outlet-port. The ports 50 and 50' lead directly to the chest into which the steam is fed through the pipe 55, while the ports 51 and 52 lead to the enclosure 60, from which extends the exhaust-pipe 61.

In the upper portion of both faces of the piston 41 are notched spring-pressed strikers 56 and 57, which as the piston reciprocates alternately engage their respective plugs to shift the valve. Thus when the piston has completed one stroke it shifts the valve to reverse it, so that the return stroke will be made.

As the direction of movement of the pistons depends upon the position of the cut-off valve, it is only necessary to properly set the valve to insure the pistons traveling initially in the desired direction. Thus by properly adjusting the valve the engine may be reversed. For shifting the valve manually it is provided with a stem 33, which extends through a stuffing-box 34 in the end of the valve-chamber, and connected to the end of which stem is a lever 35, which works over a notched segment 36. The inner end of the stem has a degree of lost motion with respect to the valve corresponding to the length of the path of movement of the valve, so that when the valve has been shifted the lever will not hold it against operation.

It will be understood that in practice modifications of the specific construction shown may be made and that the valve mechanism may be applied to any style of engine to which it is adapted.

What is claimed is—

1. An engine comprising a cylinder, a steam-chest, a valve-chamber between the cylinder and chest and communicating with the ends of the cylinder, a valve in the chamber and having studs projecting into the cylinder, inlet and outlet ports for the chest, said valve having passages for registration with the ports to communicate the chest with the ends of the cylinder alternately, a piston in the cylinder having strikers for engagement with the studs to shift the valve, and a stem for the valve passed outwardly through the cham-

ber for shifting the valve manually, the stem having a degree of lost motion with respect to the valve.

2. An engine comprising a steam-chest, a valve-chamber between the cylinder and chest and communicating with the ends of the cylinder, a valve in the chamber and having studs projecting into the cylinder, passages formed through the valve for communicating the ends of the cylinder alternately with the chest, a piston in the cylinder, strikers carried by the piston for engagement with the studs to shift the valve, and means for manually shifting the valve initially.
- 15 3. An engine comprising a cylinder, a steam-chest, a valve-chamber between the cylinder and chest and communicating with the ends of the cylinder, a valve in the chamber and

having studs projecting into the cylinder, inlet and outlet ports for the chest, said valve having passages for registration with the ports to communicate the chest with the ends of the cylinder alternately, a piston in the cylinder having strikers for engagement with the studs to shift the valve, a stem for the valve passed outwardly through the chamber for shifting the valve manually, the stem having a degree of lost motion with respect to the valve, and means for manually shifting the valve initially.

In testimony whereof I affix my signature in presence of two witnesses.

KASBERG C. GEELE.
